ULTRAVIOLET LAMP

Edward L. Koch, Williston Park, N. Y., assignor to
 George W. Gates & Co., Inc., Long Island, N. Y.,
 a corporation of New York

Application June 8, 1944, Serial No. 539,236

1 Claim. (Cl. 176—122)

This invention relates to invisible ray lamps such as are used for the activation of fluorescent or luminescent materials, and its object is to provide a novel and improved device of this type.

Another object of the invention is to provide an invisible light unit of the above type which is simple in construction, inexpensive to manufacture and assemble, and is considerably more durable than lamps previously employed for similar purposes.

Various other objects and advantages will be apparent as the nature of the invention is more fully disclosed.

Although the novel features which are characteristic of this invention are set forth more in detail in the claim appended hereto, the nature and scope of the invention may be better understood by referring to the following description, taken in connection with the accompanying drawing forming a part thereof, in which a specific embodiment has been set forth for purposes of illustration.

In the drawing:

Fig. 1 is a longitudinal sectional view through a light unit embodying the invention;

Fig. 2 is an end view thereof; and

Fig. 3 is a transverse section taken on the line 3—3 of Fig. 1.

In the following description certain specific terms are used for convenience in referring to the various details of the invention. These terms, however, are to be interpreted as broadly as the state of the art will permit.

The invisible light unit shown in the drawing comprises a tubular fluorescent lamp 1 having end terminals 2 connected to coils 3 within the lamp, and a surrounding concentric tube or shield 4 of filter material as hereinafter more fully described.

The fluorescent lamp 1 may be of any suitable type adapted to radiate ultra-violet and near ultra-violet light rays, and is usually a low pressure mercury vapor arc lamp of the so-called hot cathode low voltage type.

In practice the fluorescent lamp 1 is usually coated on the inside with a suitable phosphor or other material adapted to convert a greater proportion of the invisible radiations of the low pressure mercury arc into usable ultra-violet rays.

The filter tube 4 may be composed of any suitable translucent glass or plastic material adapted to filter out visible light rays and to pass only rays in the ultra-violet and near ultra-violet range.

For certain purposes I prefer to construct only one-half the area of the filter tube 4 shown at 4a of the above-mentioned filtering material, and the other half shown at 4b of ordinary transparent glass or plastic material. That is, the portion 4a encompassing 180° of the tube 4 may be composed of material adapted to filter out visible light rays and to transmit only rays in the ultra-violet and near ultra-violet range, while the portion 4b encompassing the remaining 180° of said tube may be composed of material adapted to pass ordinary visible light rays.

When a dual purpose shield of the above type is employed, the lamp may be rotated as a unit 15 through 180° to transmit either ordinary light or "black" light, as desired. In the latter case the invisible rays are usually directed upon some fluorescent material such as on an instrument dial for the purpose of activating and rendering 20 same visible.

The tubes 1 and 4 are secured in the desired spaced relation by means of asbestos washers 5 which are mounted adjacent the ends thereof, and the annular spaces between the tubes outwardly of said washers are sealed with fillings of 25 adhesive cement 6. For this purpose I prefer to use an adhesive cement made in paste form, which is easy to apply. The asbestos washers 5 act as stops for the cement in applying same.

It is to be understood that the above example 30 is only illustrative and that various changes and modifications may be made therein, and that the invention is capable of various uses which will be readily understood by a person skilled in the art.

What is claimed is:

A light unit comprising a tubular fluorescent lamp adapted to radiate both ultra-violet and visible light rays, a surrounding tubular shield substantially co-extensive with said tubular lamp spaced from said lamp and having a portion of its surface composed of a filtering material adapted to transmit only invisible light rays in the ultra-violet and near ultra-violet range and another portion composed of a material adapted to transmit visible light rays, annular spacers interposed between said lamp and shield adjacent the respective ends thereof, and adhesive means closing the spaces between said lamp and shield 40 outwardly of said spacers and permanently sealing said shield to said lamp in a unitary structure.

EDWARD L. KOCH.
